(57) **CLAIM**

The ornamental design for an eletronic atomizing device, as shown and described.

DESCRIPTION

FIG. 1 is a perspective view of an eletronic atomizing device showing my design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is an enlarged top plan view thereof; and,

FIG. 8 is an enlarged bottom plan view thereof.

The broken lines in the drawings depict portions of the eletronic atomizing device that form no part of the claimed design.
